(57) **CLAIM**

The ornamental design for a coffee bean roaster, as shown and described.

DESCRIPTION

FIG. 1 is a front perspective view of an embodiment of a coffee bean roaster showing the design;

FIG. 2 is a front elevational view of an embodiment of a coffee bean roaster showing the design;

FIG. 3 is a rear elevational view of an embodiment of a coffee bean roaster showing the design;

FIG. 4 is a left side elevational view of an embodiment of a coffee bean roaster showing the design;

FIG. 5 is a right side elevational view of an embodiment of a coffee bean roaster showing the design;

FIG. 6 is a top plan view of an embodiment of a coffee bean roaster showing the design; and,

FIG. 7 is a bottom plan view of an embodiment of a coffee bean roaster showing the design.

The broken line showing the coffee bean roaster is for the purpose of illustrating environmental structure and forms no part of the claimed design.
